Primary Examiner — Melanie H Tung(74) *Attorney, Agent, or Firm* — Sterne, Kessler, Goldstein & Fox P.L.C.(57) **CLAIM**

The ornamental design for a map, as shown and described.

DESCRIPTION

FIG. 1 is a front view of a map showing our new design; and, FIG. 2 is a front view of a second embodiment thereof. The area within the dot dash broken lines in the Figures forms no part of the claimed design. The dashed broken lines in the Figures showing the map and certain graphic elements of the map form no part of the claimed design.
